UNITED STATES PATENT OFFICE.

THOMAS SCOTT GRIEVE, OF LEICESTER, ENGLAND.

CIRCULAR-KNITTING MACHINE.

Application filed June 3, 1926, Serial No. 113,386, and in Great Britain June 25, 1925.

This invention relates to circular knitting machines and concerns those of the double-needle-cylinder end-to-end type. The invention is applicable to such machines having either rotary or stationary needle cylinders when equipped with what are known as inside sinkers.

In knitting machines of this kind difficulty is experienced when it becomes necessary to have access to the sinkers such for example as for renewal or replacement in the event of breakages. The sinkers are usually mounted in the bottom cylinder i. e. in a ring or "brass" fitted into the upper end of said cylinder and in order to get at said sinkers it is necessary to dismantle and remove adjacent portions of the upper parts of the machine which involves trouble and time.

The main object of the invention is to provide an improved construction and arrangement which will facilitate access to and removal of the sinkers when necessary.

The main object of the invention is achieved by the provision of means and an improved construction which enables separation of the cylinders to be effected in a ready manner whereby sufficient space for the desired purpose is provided between them.

In the preferred arrangement the top needle cylinder and its cam box are arranged as a complete assembly adapted for bodily upward movement or removal and the sinker cam in the bottom cylinder is adapted for displacement to enable the sinkers to be removed.

It is a feature of the invention that the top needle cylinder and its cam box are carried by a member which is common to both and is supported by the machine frame in such a manner that it can be raised when necessary to lift the needle cylinder and cam box from the operative position to provide the desired space thereunder for access to and removal of the sinkers.

In conjunction with the above-mentioned feature the upper portion of the sinker cam in the bottom needle cylinder is constructed and arranged so that it can be raised to permit removal of the sinkers.

In the further following description reference will be hereinafter made to the accompanying drawing wherein an arrangement constituting a practical example of the invention is shown applied to a knitting ma-

chine of the before mentioned type having 55 rotary needle cylinders.

Figure 1 is a sectional elevation, and

Figure 2 is a plan of the arrangement, the section being taken on the line 1—1 of Figure 2.

Referring to the drawings the top cylinder 1 and its cam box 2 are carried by an annular member 3 fitted into a corresponding opening in the top plate 4 of the machine frame. The cylinder is attached to a bearer 65 mounted upon ball bearings 6 and 7 in said member and keyed on a pin 8 which is screwed into the upper race 9 of the bearings 6 in order to support the carrier. The race 9 may be locked in position by a nut 10 and 70 each of these parts may be provided with tommy holes. The cam box 2 is attached to the underside of the member 3 by screws 11. The said member may be fastened in the top plate 4 in any suitable manner. Conveniently it is formed with a flange and is normally held down by clamps 12 fixed on the top plate by means of screws 13. Preferably each clamp is provided with a slot 14 so as to enable it to be moved radially to free the 80 member 3, without removing the screw.

When it is desired to have access to the sinker 15 in the bottom cylinder 16 the annular member is unfastened and raised, by hand or other means, in the top plate the 85 opening in which acts as a bearing. Means are furnished to hold the member in the raised position, and, conveniently said means consist of two (or more) pins 17 in the top plate which are normally engaged 90 by notches 18 (or slots or holes) in the flange of the annular member when the latter occupies its lower position and which thereby serve as positioning pins for said member. The pins 17 are of such a length 95 that when the annular member is raised and given a slight turning movement in the top plate so as to bring its flange over the pins, they will constitute support to hold the top cylinder at a suitable height above the bottom cylinder for the intended purpose. At a suitable point the flange of the member 3 may be provided with a notch 19 or slotted 100 to engage with a pin 20 longer than the pins 17 for the purpose of limiting the turning movement of said member. This pin may have a head to limit upward movement of the member.

The top cylinder is driven from the usual vertical shaft 21 by means of a driving pinion 22 and a gear 23, the latter being keyed on the pin 8. The pinion 22 is of such width that the gear still meshes therewith when the top cylinder is raised, thereby obviating relative movement between the two cylinders. The annular member has a gap 24 formed in it so as to enable it to clear the pinion 22 when raised and rotated.

In conjunction with the arrangement of the top cylinder and cam box just described, the upper portion of the sinker cam 25 is attached to a shouldered sleeve 26 capable of endwise movement up and down in the bottom cylinder 16. The cam sleeve has attached to it a longer sleeve 27 which extends below the bottom of the bottom cylinder and at its lower end may be knurled or have a knurled flange or be otherwise adapted for rotation by hand or by a suitable tool. The two sleeves are screwed together i. e. one screws into or upon the other.

The shouldered sleeve 26 fits in a corresponding opening in a sleeve 28 to which the lower part of the sinker cam 25 is attached, and in normal working position is held down by the sleeve 27 which is tightened against a shoulder 29 in the sleeve 28 and thus serves as a nut. When the sleeve 26 is to be raised the sleeve 27 is unscrewed by rotation down the cam sleeve and then pushed up thereby pushing the said sleeve upwards.

When as in the example just described the needle cylinders are rotary, the sleeve 28 in which the cam sleeve 26 is mounted is, of course, normally stationary within the bottom cylinder.

A cover 30 may be fixed on the top plate 4 by screws 31, said covering being provided with openings 32 in order to clear the clamps 12 which may therefore serve as locating means for the cover.

What I claim then is:—

1. In a circular knitting machine of the type herein described, a construction wherein the top needle cylinder and its cam box are carried by a flanged annular member fitted into an opening in the top plate of the machine said member being movable vertically and also rotatably to lift and hold the needle cylinder clear of the opposing bottom needle cylinder whereby space is provided between said cylinders for access to the sinkers.

2. In a circular knitting machine of the type herein described, a construction wherein the top needle cylinder and cam box are carried by a flanged annular member fitted

into an opening in the top plate of the machine and normally held down by clamps, said top plate having pins which are normally engaged by slots in the flange of the annular member, said flange after being lifted and turned, resting upon said pins to hold the needle cylinder in a raised position to provide access between it and the opposing needle cylinder for access to the sinkers in the bottom needle cylinder.

3. In a circular knitting machine of the type herein described, a construction wherein the top needle cylinder and its cam box are carried by a flanged annular member fitted into an opening in the top plate of the machine and normally held down by clamps, said top plate having pins which are normally engaged by slots in the flange of the annular member, the latter being movable vertically and also rotatably whereby its flange may be rested upon the pins to hold the top cylinder raised from the opposing bottom cylinder to provide space between said cylinders for access to the sinkers in the bottom needle cylinder, and a pin longer than said supporting pins is provided for engagement by a notch in the annular member to limit the turning movement of the latter.

4. In a circular knitting machine of the type herein described, a construction wherein the top needle cylinder is adapted to be raised from the operative position to provide space between the opposing cylinders for access to the sinkers, the upper portion of the sinker cam in the bottom needle cylinder, and a sinker cam which is adapted to be raised to permit removal of the sinkers, said cam portion being attached to a shouldered sleeve capable of endwise movement up and down in the cylinder and having screwed upon it a longer sleeve which extends below the bottom of the bottom cylinder and is adapted for rotation, said sleeve being in the normal position tightened against a shoulder in a sleeve in which the cam sleeve fits.

5. In a circular knitting machine of the type herein described, a bottom needle cylinder carrying inside sinkers and a sinker cam and provided with means for raising said cam to permit removal of the sinkers, said means comprising a vertically movable sleeve supporting the cam, and a sleeve engaging therewith and extending below the cylinder.

In testimony whereof I affix my signature.

THOMAS SCOTT GRIEVE.
